(57) **CLAIM**

The ornamental design for a part of a container, as shown and described.

DESCRIPTION

FIG. 1 is a perspective view of a part of a container showing our new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a side elevation view thereof; and,

FIG. 7 is a another side elevation view thereof.

The broken line showing of container and cap is included for the purpose of illustrating only and forms no part of the claimed design.
